PORTRABLE COMMODE

Al G. Hilde, Jr., 925-C Kingsview Lane,
Minneapolis, Minn.

Filed Apr. 12, 1965, Ser. No. 84,716

Term of patent 14 years

(Cl. D4—5)

FIG. 1 is a top plan view of a portable commode embodying my novel design;

FIG. 2 is a side elevational view of one side thereof;

FIG. 3 is a side elevational view illustrating the other side thereof;

FIG. 4 is a rear end elevational view thereof;

FIG. 5 is a front elevational view thereof; and

FIG. 6 is a bottom plan view.

I claim:

The ornamental design for a portable commode as shown.
